UNITED STATES PATENT OFFICE

BERNARD SHIVEK, OF DORCHESTER, MASSACHUSETTS, ASSIGNOR TO SAMUEL WERLIN,
OF MALDEN, MASSACHUSETTS, AND MORRIS B. WHITE, OF CHELSEA, MASSACHU-
SETTS

DESIGN FOR AN ICE CREAM CONE

Application filed June 25, 1931. Serial No. 40,320. Term of patent 3½ years.

To all whom it may concern:

Be it known that I, BERNARD SHIVEK, a citizen of the United States, residing at Dorchester, county of Suffolk, Commonwealth of Massachusetts, have invented a new, original, and ornamental Design for Ice Cream Cones, of which the following is a specification, reference being had to the accompanying drawings forming a part thereof.

In the drawings, Figs. 1, 2 and 3 are respectively front, rear and side views of an ice cream cone showing my new design.

I claim:

The ornamental design for an ice cream cone, as shown.

BERNARD SHIVEK.
